UNITED STATES PATENT OFFICE

159,326

TRAILER

Joseph G. Eldridge, Peru, Ill.

Application April 20, 1948, Serial No. 145,833

Term of patent 3½ years

(CL. D14—3)

To all whom it may concern:

Be it known that I, Joseph G. Eldridge, a citizen of the United States of America, residing at Peru, in the county of La Salle and State of Illinois, have invented a new, original, and ornamental Design for a Trailer, of which the following is a specification, reference being had to the accompanying drawing, forming part thereof.

Fig. 2 is a side perspective view showing the opposite side of the trailer.

Fig. 3 is a view of the interior of the trailer looking towards the rear from approximately the center.

Fig. 4 is a view looking at the interior of the trailer towards the front from approximately the center.

The characteristic features of my design reside in the interior portions of the trailer shown in Figs. 3 and 4 of the drawing.

I claim:

The ornamental design for a trailer, as shown and described.

JOSEPH G. ELDREDGE.
